(57) **CLAIM**

The ornamental design for a pair of in ear headphones, as shown and described.

DESCRIPTION

FIG. 1 is a perspective view of a pair of in ear headphones showing our new design, the cords are drawn broken away for indeterminate length;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines of the pair of in ear headphones form no part of the claimed design.
